[57] CLAIM

The ornamental design for a conveyor assembly portion with variable offset arms for supporting poultry and poultry parts, as shown and described.

DESCRIPTION

FIG. 1 is a perspective view of a conveyor assembly portion with variable offset arms for supporting poultry and poultry parts, showing my new design;

FIG. 2 is a side elevational view thereof, the other side being a mirror image;

FIG. 3 is a top plan view thereof; and,

FIG. 4 is an end elevational view thereof, the opposite end being a mirror image.

The broken line showing of cones, half-pads, and framing is for illustrative purposes only and forms no part of the claimed design.
